UNITED STATES PATENT OFFICE.

WILLIAM L. BARRON, OF NEW YORK, N. Y., ASSIGNOR TO THE SINGER MANUFACTURING COMPANY, A CORPORATION OF NEW JERSEY.

BUTTON-SEWING MACHINE.

1,085,786.

Specification of Letters Patent.

Patented Feb. 3, 1914.

Application filed April 12, 1912. Serial No. 690,412.

To all whom it may concern:

Be it known that I, WILLIAM L. BARRON, a citizen of the United States, residing at New York, in the county of New York and 5 State of New York, have invented certain new and useful Improvements in Button-Sewing Machines, of which the following is a specification, reference being had therein to the accompanying drawings.

10 This invention has for its primary object to provide a button-holder for the easy introduction and removal of the so-called "self-shank" buttons or those formed at the back with a projection or protuberance 15 integral with the body of the button to receive the fastening stitches.

As preferably constructed, the button-holder is secured to a spring-pressed presser-bar of a sewing machine and comprises two 20 gripping-jaw carrying levers connected together for reciprocal movement and normally forced toward each other by a continuously acting spring and by an intermittently acting spring whose action is designed to be interrupted by the lifting of the 25 button-holder for introduction and removal of the buttons. The button gripping jaws are preferably of conical form upon a common axial line and are provided with overhanging lips affording button-retaining shoulders against which the edges of the 30 buttons are forced by the inclination of the jaws toward the same, whereby the rearward faces of the buttons having the shanks, 35 for buttons of various patterns, are located uniformly in relation to the needle-path.

The machine is preferably provided with a raised work-support at one side of which the button-holder is disposed, and upon the 40 top of which normally rests the presser-foot which is mounted upon a spring-pressed presser-bar journaled in the machine-frame independently of the bar to which the button-holder is attached. A common lifter is 45 arranged for successive engagement with the two presser-bars so as to lift first the button-holder and then the presser-foot.

By the means just described, the position 50 of the button-holder relative to the work-support may be adjusted for the largest sized buttons for which it is adapted, and the attachment is thus adapted for attaching the buttons to fabrics of very widely varying thicknesses, the lift of the button-

holder not being dependent in any degree 55 upon the thickness of the material and requiring no change for variations in thickness of the material to which the buttons are attached. This is true particularly because the button performs no function in the holding of the material, and is automatically centered at the same level within the gripping jaws by reason of the concavity of the latter upon their common axis transverse to the needle-path.

60 In the accompanying drawings, Figure 1 is a side elevation and Fig. 2 a front end elevation of a button sewing machine embodying the present invention. Fig. 3 is a perspective view of the button-holder, 65 presser-foot and work-support. Fig. 4 is a perspective view of the stop device for the jaw-carrying levers, and Fig. 5 a similar view of the work-support. Fig. 6 is a detail transverse section of the presser-bar 70 lifting lever and a portion of the sewing machine frame. Fig. 7 is a side elevation of the attachment, and Figs. 8 and 9 are respectively, top and bottom views of the button-holder. Fig. 10 is an end view of the jaw- 75 carrying levers with the gripping jaws in face view and Fig. 11 an enlarged transverse sectional view of the gripping jaws with a button held therein. Fig. 12 is a perspective view of the frame member containing the 80 slideway for the presser-foot carrying bar. Fig. 13 is a side elevation of the frame member containing the 85 slideway for the presser-foot carrying bar.

The machine is shown constructed with a frame comprising the hollow standard 1 with the lateral work-sustaining arm or horn 2 and the hollow overhanging arm 3 in 90 which latter is journaled the main-shaft 4 carrying at its rearward end the fast and loose pulleys 5 and 6 and at the forward end the take-up cam-cylinder 7 provided with the crank-pin 8 connected by means of the 95 pitman 9 with the usual stud upon the collar 10 fixed upon the needle-bar 11 which carries the eye-pointed needle 12. The reciprocating needle-bar 11 is journaled in the swinging frame 13 fulcrumed within the 100 head of the bracket-arm and provided with a lateral arm 14 operatively connected by suitable means, including the link 15, with the groove 16 of the cam-cylinder 17 deriving step-by-step rotary movements from a 105 suitable connection with the main-shaft 4.

Cooperating with the needle 12 is the oscillating shuttle 18 journaled in the race 19

and provided with the thread-case 20. The shuttle is actuated by means of the driver 21 at the forward end of the rock-shaft 22 mounted within the horn 2 and having at 5 its rearward end the crank 23 connected, in a manner well known, by means of the rocker 24 and pitman 25 with the actuating crank 26 of the main-shaft.

Upon the outer end of the work-sustaining arm 2 is secured, by means of screws 27 entering apertures 28 therein, the throat-plate 29 which is formed with a raised work-support 30 adjacent which it is provided with the button-head clearance cavity 31. 15 The work-guiding lip 32 rises from the top of the support 30, which is channeled transversely to receive the block 33 secured removably in position by means of the screw 34. The needle-slot 35 extends partly 20 through the block 33 and partly through the plate 29, and the block 33 is provided adjacent the same with the button-shank cavity 36.

Journalized in the head of the bracket-arm 25 is the presser-bar 37 upon which is adjustably secured by means of the set-screw 38 the collar 39 having a forked arm 40 embracing the guide-rod 41 and the upwardly projecting arm 42 having a lateral lug 43 adapted 30 for engagement by the forward arm 44 of the lifting lever mounted upon the fulcrum screw-stud 45 sustained by the frame, and having a rearwardly extending arm 46 with a lateral lug 47 which carries a stop-screw 48 35 held from turning by the lock-nut 49 and having its point normally resting upon the flange 38 of the bracket-arm 3, as represented in Figs. 1 and 6. The function of the screw 48 is to afford an adjustable stop for limiting the descending movement of the rock- 40 lever 44-46 under the action of the spring 50 surrounding the presser-bar and interposed between the collar 39 and the upper bearing of the bar 37.

45 Secured to the lower end of the presser-bar by means of the screw 51 is the shank 52 of the laterally extending frame-plate 53 formed with a slot 54 through which passes the stud-screw 55 having a clamp-nut by 50 means of which is secured adjustably in place the plate 57 sustaining the operative parts of the button-holder. At its rearward end, the plate 57 has the depending shoul- 55 dered stud-screws 58 upon which are ful- crumed the jaw-carrying levers 59 and 60 each provided with a down-turned extension 61 affording a button-gripping jaw. The levers 59 and 60 are formed adjacent their fulcrumed ends with the intermeshing 60 toothed sectors 62 by means of which they are caused to move toward and from each other reciprocally, being drawn together by means of the continuously acting springs 63 connected at opposite ends by means of the 65 screws 64 with the levers 59 and 60. The

adjacent edges of the gripping jaws 61 are formed with concaved conical gripping surfaces 61^a having a common axis of curvature transverse to the needle-path in the plane of said jaws, and secured to the forward faces of said jaws at opposite sides of the needle-path, and at the edges having the larger curvature are the button-confining plates 65 which are secured thereto in slightly inclined relation as represented in Fig. 11, by means of the screws 66, so that their edges overhang to afford sustaining lips for the adjacent margins of the button thrust against the same by the flaring operative faces of the jaws. The plates 65 are preferably inclined forwardly so as to provide for buttons having curved backs or rearward faces.

Secured upon the top of the holder-plate 57 intermediate the stud-screws 58 by means of the screw 67 and washer 68 is the angular portion 69 of a yoke-shaped spring formed with the spaced arms 70 and 71 extending forwardly and each resting against the outer edge of one of two independent slide-bars 72 journalized in alined transverse slideways in the upwardly extending lugs 73 of the frame-plate 53 and having inwardly extending portions 74 normally resting upon the outer edges of the levers 59 and 60. The 90 spring-arms 70 and 71 act upon the arms 59 and 60 through their respective slide-bars 72 to apply an additional clamping pressure to the button-gripping jaws to insure the holding of the button firmly during the 95 stitching operation. The adjacent upper corners of the slide-bars 72 are rounded to receive the wedge-shaped lower extremity 75 of a rigid retracting arm or retractor 76 having a foot 77 formed with an aperture 78 to receive a fastening screw-stud 79 with clamp-nut 80 for securing said arm in position. When the presser-bar 37 is lowered, as represented in Fig. 7, the slide-bars 72 are 100 disengaged from the wedge-shaped extremity 75 of the arm 76, but when the presser-bar and button-holder are lifted, the slide-bars 72 are brought into engagement with the arm 76 and forced apart as represented in Fig. 3, thereby relieving the jaw-carrying 105 arms 59 and 60 of the pressure of the spring-arms 70 and 71 and permitting them to grip the opposite edges of the button merely under the light action of the primary spring 68, so that after a stitching operation the 110 button may be easily replaced by a new one.

Fulcrumed upon a screw-stud 81 depending from the holder-plate 57 is an angle-lever formed with arms 82 and 83, the latter of which carries a fulcrum screw-pin 84 embraced by one apertured end of a link 85 whose other end has an elongated aperture 86 loosely embracing the stud-pin 87 upon the lower side of the jaw-carrying lever 59. The end of the other arm 82 of the angle- 115 120 125 130

lever has a boss 88 provided with a threaded aperture to receive the shank 89 of a clamp-screw passing through a slot 90 in a lateral extension 91 of the holder-plate 57 and provided with a head 92 by means of which the angle-lever may be set in different positions to adjust the position of the fulcrum pin 84. In practice, the elbow-lever 82 83 is so set that the inner end of 10 the aperture 86 of the link 85 will afford a stop for the stud-pin 87 so as to space apart the concave faces 61^x of the jaws 61 a distance slightly less than the diameter of the button to be gripped.

15 While the spring-arms 70 and 71 are retracted, the insertion of the edges of the button between said jaws forces them apart slightly, but less than the range of movement permitted by the length of the aperture 86 of the link 85, thus providing for the free opening and closing of the jaws within narrow limits. To accommodate a button of different size, it is merely necessary to suitably shift the angle-lever 82 83, 25 which changes the range of movement and working positions of the jaw-carrying levers while maintaining the same restriction of their degree of opening and closing movement. In practice, the jaw 61 of the 30 lever 60 is made shorter than that of the other lever to facilitate the edgewise withdrawal of a button stitched to the fabric after the lifting of the button-holder.

Opposed to the upper operative face of 35 the work-support 30 is the presser-foot 93 formed in one edge adjacent the button-holding jaws with the needle-aperture 94 and having its shank in the form of a bar 95 having a laterally extending arched upper end 96 and fitted within a vertical guide-way 97 of the depending rigid arm 98 and having an aperture 99 entered by a screw 100 by means of which it is secured to the lower end of the bracket-arm head. The 40 bar 95 is normally pressed downwardly by means of a spring 101 secured at one end by means of the screw 102 to the lower end of the bracket-arm head with its other extremity resting upon a stud-pin 103 tapped 45 into the bar 95 and passing through a slot 104 in the arm 98 in which the bar 95 is confined by means of the cap-plate 105 secured thereon by screws 106.

The extremity of the arched upper portion 50 of the presser-bar 95 is adapted for engagement with a laterally extending lug 107 of the collar 39, but is in practice disposed more or less above said lug, depending upon the size of the button for which the 55 holder is set, so that the tilting of the lifting lever 44 46 causes the successive raising of the button-holder and presser-foot differentially, their respective lifting movements being determined by the size of the button 60 and the thickness of the material interposed

between the presser-foot and the top of the work-support.

Ordinarily, the initial position of the lifting lever 44 46 is so adjusted by means of the stop-screw 48 as to bring the axis of curvature of the gripping jaws at substantially the level of the upper face of the work-support 30. As each of these jaws is inclined divergently from their common axis, it will be observed that through the 70 combined action of the jaw-closing springs 63 and 69, 70, 71 upon the levers 59 and 60, the opposite edges of the button are gripped at the points of tangency and on the said axial line, whereby all 80 symmetrically formed buttons will have their shanks presented, not only centrally of the plane of movement of the jogging needle but at substantially the same level and within the cavity 36. It is obvious that the terms "conical" and "curved" as employed herein relatively to the button-gripping jaws, has reference to the divergent inclination of the parts thereof determining the level at which the button is held, and are to be understood 85 in reference to function of this feature rather than to mere geometrical shape.

In the use of the machine fitted with the present improvement, the rock-lever 44 46 is first tilted to raise the button-holder and presser-foot, thereby retracting the spring-arms 70 and 71 and permitting the operation only of the light spring 63 upon the gripping jaws 61. A button *b* is then 90 pressed inwardly from the rear, the jaws being wedged apart by the rounded edge of the button and then closing in to grip the button as the rim of the latter comes in contact with the retaining plates 65 against which it is pressed by the flaring form of 95 the surfaces 61^x as represented particularly in Fig. 11. The button-shank *b'* is thus caused to enter the cavity 36 of the block 33 with its transverse aperture within the range 100 of movement of the needle upon one of its strokes. The material *m* is then doubled over and introduced between the presser-foot 93 and the work-support 30 with its folded edge in contact with the end of the button-shank *b'* and the guide-lip 32. The work-holder and presser-foot are then lowered, the lower edge of the button, if a large one, entering the cavity 31 of the throat-plate 29, 105 after which the machine is set in motion and a series of fastening stitches is applied in a manner well known. At the completion of the fastening operation, the rock-lever 44 46 is again tilted to lift the button-holder and presser-foot and the work is withdrawn toward the front of the machine after the 110 button has been pressed downwardly to free it from the gripping jaws.

Having thus set forth the nature of the invention, what I claim herein is:—

1. A button-holder comprising gripping 130

jaws, means including a spring for forcing said jaws upon a button to be gripped, and means for reducing the gripping force upon said button to a predetermined minimum, 5 said means completing its operation without disturbing the gripping position of said jaws.

2. A button-holder comprising gripping jaws, means for maintaining a light gripping force upon said jaws and means for increasing the gripping force upon said jaws at predetermined periods.

3. A button-holder comprising opposed gripping jaws, a continuously acting spring 15 for forcing said jaws toward each other, a second spring also adapted to force said jaws toward each other, and means for rendering ineffective the second-named spring.

4. A button-holder comprising opposed concaved gripping jaws having a common axis of curvature, a continuously acting spring for forcing said jaws toward each other, a second spring also adapted to force said jaws toward each other, and means for 25 relieving said jaws of the action of the second-named spring.

5. The combination with stitch-forming mechanism including a reciprocating needle, of a button-holder comprising opposed concaved conical gripping jaws having a common axis of curvature and disposed in a plane substantially parallel with the needle-path and provided with overhanging lips at the edges of larger curvature, a spring for 30 forcing said jaws toward each other, and a connection between said jaws whereby they are caused to advance and recede equally.

6. A button-holder comprising a pair of levers connected for reciprocal movement 40 and each carrying a button-gripping jaw, a spring for drawing said levers together, a laterally adjustable fulcrum-pin, a stud-pin carried by one of said levers, and a slotted link connecting said pins, one of 45 which is loosely embraced by the aperture of said link, and adapted to limit the lateral movement of said lever.

7. A button-holder comprising two gripping-jaw carrying members connected for 50 reciprocal movement, a spring for forcing

them toward each other, a double-armed spring embracing said levers and adapted also to force them toward each other, and positively acting means for spreading said spring-arms to retract them from operative 55 relation with their respective jaw-carrying members.

8. In a sewing machine, in combination, two substantially parallel and independently reciprocal bars, a work-support, a button-holder secured to one of said bars and sustained thereby at one side of the work-support, a presser-foot secured to the other of said bars and disposed adjacent the button-holder and above the work-support, and 60 means for differentially lifting said bars.

9. In a sewing machine, in combination, two substantially parallel and independently reciprocal bars, a work-support, a button-holder secured to one of said bars and sustained thereby at one side of the work-support, a presser-foot secured to the other of said bars and disposed adjacent the button-holder and above the work-support, and 65 means, including a common lever, adapted to successively engage said bars for differentially lifting said button-holder and presser-foot.

10. In a sewing machine, the combination with a spring-pressed presser-bar, of a button-holder comprising reciprocally moving members carrying opposed gripping jaws, a continuously acting spring acting upon 70 said members to force said jaws toward each other, means including a second spring also acting upon said members to force said jaws toward each other, a retractor normally disengaged from said means whereby the action of the second-named spring upon said members may be interrupted, and a presser-bar lifter 75 whereby said means are brought into operative relation with the retractor.

In testimony whereof, I have signed my name to this specification, in the presence of two subscribing witnesses.

WILLIAM L. BARRON.
